UNITED STATES PATENT OFFICE.

ALCORN RECTOR, OF NEW YORK, N. Y., ASSIGNOR, BY MESNE ASSIGNMENTS, TO RECTOR
GAS LAMP COMPANY, OF NEW YORK, N. Y., A CORPORATION OF NEW YORK.

GAS-LAMP.

No. 893,872.

Specification of Letters Patent. Patented July 21, 1908.

Application filed September 26, 1906. Serial No. 336,277.

To all whom it may concern:

Be it known that I, ALCORN RECTOR, of the city, county, and State of New York, have invented a new and Improved Gas-
5 Lamp, of which the following is a full, clear, and exact description.

My invention relates to improvements in incandescent gas lamps and more especially to improvements in the inverted lamps so-
10 called in which a depending mantle is used and the gas and air are forced downward into the mantle. An objection to most lamps of this kind is that it is difficult to apply the
15 mantles to the lamps for the reason that the burner or pipes are in the way and as the mantles are extremely fragile one is quite likely to injure them in placing them upon the lamp.

The object of my invention is to obviate
20 this difficulty and produce a lamp in which the mantle carrying part and the gas delivering part are separable so that when separated the mantles can be readily applied or removed without the least difficulty, after
25 which the parts can be readily placed in the proper relation for use. Obviously this result can be obtained in quite a number of ways and in the drawings I have shown several methods to make it clear that my invention
30 is not confined to any precise form of burner in which the delivery part and the mantle carrying part are separable.

Reference is to be had to the accompanying drawings forming a part of this specification, in which similar letters and figures of reference indicate corresponding parts in all the views.

Figure 1 is a side elevation of the lamp embodying my invention with the head and gas pipes raised from the mantles; Fig. 2 is a broken side elevation of a slightly modified form of the invention showing also the parts separated; Fig. 3 is a broken side elevation of another modification of the lamp in which
45 the parts are applied to the usual upright gas jet; Fig. 4 shows in side elevation the application of the principle to the so-called gas arc lamp.

Referring to Fig. 1, the bunsen 10 is provided with a supporting pin 11 or equivalent which supports the sliding yoke 12 and this is attached to the sleeve 13 and has rings 12^a which are adapted to support the legs 14^a of

the inverted mantles 14. The mantles, as is well known to the trade, are usually provided with rings of magnesium or other material at the top having legs 14^a which fit in sockets on the burner heads, but in this case the legs 14^a which are exactly as usual, rest in sockets in the rings 12^a. The sleeve 13 is provided with a bayonet slot 15 which is adapted to connect with a pin 16 near the top of the tube 17 which forms an extension of the bunsen 10, so that when the sleeve 13 is raised and locked to the pin 16 the mantles 14 will be in the position shown in dotted lines in Fig. 1, so as to receive the gas and air from the tubes or pipes 19 which extend downward from the head 18 on the upper part of the stem or tube 17. Obviously other fastening-means can be used for connecting the sleeve 13 to its guide and supporting stem without affecting the principle of the invention.

In Fig. 2 I have shown a slight modification of the device in which the rings 12^a are rigidly supported at the top of the tube 17 by arms 12^b which are attached to the tube and the top of the tube is preferably widened slightly as at 17^a. In this case the head 18 has the depending tubes 19 as shown and it has also a pipe 20 which is tapered as at 20^a so as to fit into the part 17^a of the tube 17. In this structure the head 18 and tubes 19 are lifted off, thus leaving the mantles 14 free and clear so that they can be readily removed from or inserted in the rings 12^a. The structure shown in Fig. 2 and the structure shown in Fig. 1 can be attached to any ordinary gas pipe and used with any preferred type of glass ware or globe.

In Fig. 3 I have shown a slight modification of the invention applied to the ordinary vertical jet and with a single inverted mantle 14 which is carried as already described, and the single ring 12^a is attached to the sleeve 13 which moves up and down on the stem 17, as in Fig. 1, but the stem or tube 17 has a single bend 19^a and has a pin 16 as already described. The sleeve 13 can be dropped downward into contact with the supporting pin 11 or it can be pushed up to have the pin 16 locked into the bayonet slot 15 in the former case the mantle being lowered to permit ready access to it and in the latter the mantle being raised ready for lighting.

In Fig. 4 I have shown a structure analogous to the so-called arc lamp, this term being applied to groups of mantles which are generally inclosed by a single globe to give an arc light effect, and in this case a plurality of stems 17 are used having the fixed rings 12^a as already described, but the stems each deliver into an inverted U-shaped pipe or tube 19^b which can be placed on or removed from the tube 17 and by removing it the mantle is left free and by placing it in position the lamp is ready for lighting.

I have shown these several modifications to illustrate the fact that there are very many ways of separating from each other the pipe which delivers the gas and air, and the mantle. Obviously any approved form of bunsen can be used and any ordinary or preferred type of mantle, and it will be seen that my invention is not confined to any particular means of separating the mantle and delivery pipes.

It will be observed that in the several views I have shown rings in which the mantles can be deposited by simply dropping them through the rings, and this is important because where the mantle has to be pushed upward into some sort of a holder, it is very likely to be broken during the operation.

Having thus fully described my invention, I claim as new and desire to secure by Letters Patent,—

1. In combination, a Bunsen tube, a bracket carried by the Bunsen tube, a mantle carried by the bracket, and a pipe bent into an approximate U-shape engaging the top of the Bunsen tube, and discharging within the mantle, said pipe being removable independent of the Bunsen tube and the mantle.

2. In combination, a Bunsen tube, a bracket carried by the Bunsen tube and extending to one side thereof, a mantle carried by the bracket and a pipe removably engaging the top portion of the Bunsen tube and discharging within the mantle, said pipe being removable independent of the Bunsen tube and the mantle.

3. In combination, a Bunsen tube, a bracket carried by the Bunsen tube, a mantle carried by the bracket, and a pipe bent into an approximate U-shape and supported on said Bunsen tube, and discharging within the mantle, said pipe being removable independent of the Bunsen tube and the mantle.

ALCORN RECTOR.
